Primary Examiner — Darlington Ly(74) *Attorney, Agent, or Firm* — Mitchell Law PLLC; Matthew W. Mitchell(57) **CLAIM**

The ornamental design for an electric powered scooter, as shown and described.

DESCRIPTION

FIG. 1 is a front perspective view of the electric powered scooter of the present invention;
FIG. 2 is a side view of the invention of FIG. 1, as seen from the right side of FIG. 4;

FIG. 3 is a side view of the invention of FIG. 1, as seen from the left side of FIG. 4;
FIG. 4 is a front view of the invention of FIG. 1;

FIG. 5 is a back view of the invention of FIG. 1;
FIG. 6 is a top view of the invention of FIG. 1; and,
FIG. 7 is a bottom view of the invention of FIG. 1.

The broken lines in the drawings illustrate portions of the electric powered scooter that forms no part of the claimed design.

1 Claim, 6 Drawing Sheets(56)
